Chasnow & Co.

UNITED STATES PATENT OFFICE.

MARCELLUS H. MERRILL, OF NEW LEBANON, NEW YORK, ASSIGNOR OF
ONE-THIRD TO ABBIE W. GILLETT, OF SAME PLACE.

CAR-CO尤LING.

SPECIFICATION forming part of Letters Patent No. 514,483, dated February 13, 1894.

Application filed May 17, 1893. Serial No. 474,533. (No model.)

To all whom it may concern:

Be it known that I, MARCELLUS H. MERRILL, a citizen of the United States, residing at New Lebanon Centre, in the county of 5 Columbia and State of New York, have invented a new and useful Car-Coupling, of which the following is a specification.

The invention relates to improvements in car couplings.

10 The object of the present invention is to provide a simple, inexpensive and efficient car coupling, which may be readily coupled and uncoupled without necessitating going between cars, and which will be adapted to 15 couple with the ordinary pin and link coupling.

The invention consists in the construction and novel combination and arrangement of parts hereinafter fully described, illustrated 20 in the accompanying drawings and pointed out in the claims hereto appended.

In the drawings—Figure 1 is a perspective view of a car coupling constructed in accordance with this invention. Fig. 2 is a horizontal sectional view. Fig. 3 is a reverse plan view. Fig. 4 is a detail perspective view of the link.

Like numerals of reference indicate corresponding parts in all the figures of the drawings.

30 1 designates a hook draw-head, having an upward extension 2 to be engaged by a link 3 of another draw-head and mounted between sills 4 and cushioned by a spring 5 in the usual manner. The vertical extension 2 forms a hook; and the draw-head is provided with a coupling pin perforation 6 and has a recess 7 to enable the ordinary pin and link coupling to be employed, when coupling with 35 cars having that form of coupling. The link 40 3 is V-shaped, and has the inner ends of its sides mounted on journals or pintles 8 of side plates 9, which are arranged on the outer side faces of the sills 4, and are connected with the draw-head by a cross-bar 10, extending 45 through slots 11 of the sills, and an opening of the draw-head, whereby the upwardly swinging link moves with the draw-head, and is cushioned by the spring thereof. The 50 link is secured on the journals or pintles of the side plates by keys; and the side plates

are similarly attached to the ends of the cross-bar 10. The rear side of the vertical extension 2 of the draw-head is rounded, and the front or apex of the link is rounded to correspond with the draw-head, and it will be apparent that the draft is centrally on the draw-head, and is cushioned by the draft spring. One side of the link is provided with a depending arm 12, which is connected by a 55 chain 13 with a spring 14; and the latter is mounted beneath a car 15 on the frame thereof. The weight of the link is sufficient to hold it securely in engagement with the draw-head; but the spring operates to prevent any rattling or jarring and makes it absolutely impossible for the link to be accidentally thrown upward out of engagement with a draw-head. The link is elevated for coupling by a rock-shaft 16, arranged at each 60 side of the car and provided at its inner end with an angle arm 17 to engage the lower edge of the adjacent side of the link, and at its outer end with a handle arm 18 arranged on the adjacent side of the car. The handle 65 arm is drawn inward and downward sufficiently to elevate the link above the draw-head; and the link is held in this position by a pin 19, which is inserted in a socket 20 of the car to form a stop for the handle of the 70 rock-shaft. The pin 19 which is connected by a chain 21 with the car, is withdrawn after the cars to be coupled come together and the link falls by gravity into engagement with the draw-head. The rear wall of the extension 2 of the draw-head is vertical; and the link may be readily lifted out of engagement with the draw-head by either of the 75 rock-shafts.

It will be seen that the car coupling is simple and comparatively inexpensive in construction, that it is capable of being readily coupled and uncoupled without going between cars, and that it will readily couple with cars having the ordinary pin and link coupling.

Changes in the form, proportion, and the minor details of construction may be resorted to without departing from the principle or sacrificing any of the advantages of this invention.

What I claim is—

1. In a car coupling, the combination of a

car provided with sills having longitudinal slots, a hook draw-head mounted between the sills and having an opening, a cross-bar extending through the opening of the draw-head and the slots of the sills, side plates secured to the ends of the cross-bar, and a link having its sides hinged to the side plates, substantially as described.

2. In a car coupling, the combination of a car having sills provided with longitudinal slots, a draw-head mounted between the sills and provided with an opening, a cross-bar extending through the opening of the draw-head and the slots of the sills, side plates secured to the ends of the cross-bar and pro-

vided with journals, a link having its sides mounted on the journals and provided at one side with a depending arm, a spring connected with the arms and adapted to draw the link downward, and a rock-shaft having an arm adapted to engage the lower edge of the link to lift the same, substantially as described.

In testimony that I claim the foregoing as my own I have hereto affixed my signature in the presence of two witnesses.

MARCELLUS H. MERRILL.

Witnesses:
